UNITED STATES PATENT OFFICE.

CLARKE R. LAKE, OF PEORIA, ILLINOIS.

COMBINATION COACH-WINDOW LOCK AND HANDLE.

Application filed December 13, 1924. Serial No. 755,658.

To all whom it may concern:

Be it known that I, CLARKE R. LAKE, a citizen of the United States, residing at Peoria, in the county of Peoria and State of Illinois, have invented certain new and useful Improvements in Combination Coach-Window Locks and Handles, of which the following is a complete specification.

This invention relates to a combination window lock and handle to be used with windows of railway passenger coaches or in connection with the windows of any public conveyance where the same is held in position by notches located in the window casing, in lieu of the well known weight.

The primary object of this invention is the provision of a handle for coach windows which includes means for operating the retaining means positioned at either edge of said window.

A further object of this invention is to provide a handle of the above mentioned character which also includes means for operating an additional latch arranged to connect the two windows together for simultaneous movement.

A still further object of this invention is the provision of connections to both latches, operable directly from the lifting handle, for releasing both latches.

An even further object of the present invention is to provide an outer coach window with a series of vertically arranged notches and a co-acting latch therefor carried by the inner window for engaging or disengaging such notches, and controllable through suitable connections to the lifting handle of the inner window.

With these general objects in view as well as minor objects which will appear as the invention is more thoroughly set forth in the following specification, the same will now be described by reference to the accompanying drawing, in which:

Figure 1 is a face view of an inner window of a coach showing the relative position of the lifting handle and latch operating means housing.

Fig. 2 is an enlarged horizontal section on line II—II of Fig. 1, showing both coach windows and the invention in place.

Fig. 3 is a detail section of the inner window latch taken on line III—III of Fig. 2.

Fig. 4 is a similar section of the outer

window latch taken on line IV—IV of Fig. 52; and,

Fig. 5 is a modified form of the invention, showing the latch, operating means and handle in use with a single window.

Referring at this time to the drawings 60 in detail, wherein similar reference characters refer to analogous parts throughout the several views, and, wherein 6 and 7 designate the ordinary inner and outer windows respectively of a railway coach, and 8 the 65 window casing in which windows 6 and 7 are slidably set for vertical movement.

It is common to place a plunger 9, actuated by a coil spring 10 in the frame of coach windows of this type to securely hold 70 the same in the desired position by causing plunger 9 to engage one of a series of adjacent notches 11 carried or cut into casing 8.

Heretofore, it has been necessary for the 75 passenger to operate plunger 9 and lift window 6 at the same time, a most impossible feat practically one-half the time. Also, each window had to be raised separately.

To obviate this difficulty, and to add still 80 further convenience in operating both single and double coach windows, the well known plunger 9 with its spring 10 has been mounted in one end of a housing 11, the other end of which terminates at or near the center 85 of window 6 to form handle 12.

Window 6 is also provided with an angularly, outwardly projecting plunger 13 which extends to outer window 7 and engages a series of vertically arranged notches 90 14 formed within the frame of said outer window 7 and positioned as shown in Fig. 4. A spring 15 exerts the necessary pressure to retain plunger 13 in the projected position and, a lug 16 permits of a downward force being applied to window 7 by plunger 13 when it is desired to lower both windows at once.

Referring at this time to the operating means for the above-described plunger 9, 100 the same may, though not necessarily, consist of a cable 17 connected thereto in any suitable manner which passes along through passage 18, formed within housing 11, to a trigger 19, or other means operable through 105 engagement with the operator's finger, which is pivotally connected as at 20 to handle 12.

Plunger 13 is similarly connected by cable 21 to a trigger 22 which is slidably mounted within handle 12 as shown in Fig. 2, and provided with a helical spring 23 for maintaining the same in released position.

Cable 21 is also attached to cable 17 at a point between plunger 13 and plunger 9 which permits of the simultaneous operation of both plungers by operating trigger 22.

10 Cylindrical portion 24 travels in cavity 25 of handle 12 and precludes any binding when trigger 22 is operated.

Operation.

15 Inner window only is raised by operating trigger 22, which draws cable 21 and releases plunger 13 from notches 14 of outer window 7.

When it is desired to lower inner window 6, trigger 19 is operated to pull cable 17, thus releasing plunger 9 from engagement with notches 11.

Both windows may be raised by operating trigger 19, since they are normally connected for this movement through plunger 13 and notches 14.

When both windows are raised, they may both be lowered by dropping inner window to a level with outer window and permitting plunger 13 to engage lug 16, this is done by operating trigger 19 which only releases plunger 9.

Simple directions for operating the new window lock and handle may be conveniently placed for the passenger if desired.

Having thus described the invention, and desiring to be limited only by the scope of the appended claims, what is claimed is:

1. In a coach double window lock and handle, a lifting handle mounted on the frame of the inner window, means carried by said inner window frame for releasably engaging a series of notches formed on said outer window frame, and means operable 45 from said lifting handle for actuating said outer window engaging means.

2. In a coach double window lock and handle, a lifting handle mounted on the frame of the inner window, means carried 50 by said inner window frame for releasably engaging a series of notches formed vertically along the inner side of said outer window frame, operating means for said engaging means, a housing for said operating

means and actuating means supported by said lifting handle for actuating said outer window engaging means.

3. In a coach double window lock and handle, a lifting handle mounted on the frame of the inner window, means slidably mounted within said inner window frame for engaging a series of notches formed vertically along the inner side of said outer window frame, actuating means for said slidably mounted engaging means carried by said lifting handle, a flexible connecting cable joining said engaging means and said actuating means whereby the inner window may be raised either independently of or simultaneous with said outer window.

4. In a coach double window lock and handle, a lifting handle mounted on the frame of the inner window adjacent the center thereof, means carried by said inner window frame for engaging a series of notches formed vertically along the inner side of said outer window frame, means operable from said handle for actuating said engaging means and means integral with said outer window frame for coating with said engaging means whereby said outer and inner windows may be lowered simultaneously.

5. In a coach double window lock and handle, a lifting handle mounted on the frame of the inner window, means mounted within said inner window frame for engaging a series of notches formed by the outer window frame, means mounted within said inner window frame for engaging a series of notches formed by the window casing adjacent the edge of said inner window, flexible connections to both engaging means extending to said handle and means within said handle for actuating the said notch engaging means through said flexible connections.

6. In a coach double window, a lifting handle mounted on the inner window frame and means including a slidably mounted trigger carried by and operable from said handle for selectively causing the windows to be coupled for raising or lowering together, substantially as set forth.

In testimony whereof I hereunto affix my signature this 2nd day of December, 1924.

CLARKE R. LAKE.
